UNITED STATES PATENT OFFICE.

JULES H. STEAN, OF OMAHA, NEBRASKA.

FLOUR SIFTER.

Application filed July 3, 1922. Serial No. 572,462.

To all whom it may concern:

Be it known that I, JULES H. STEAN, a citizen of the United States, residing at Omaha, in the county of Douglas and State 5 of Nebraska, have invented certain new and useful Improvements in a Flour Sifter, of which the following is a specification.

This invention has for its object to provide a sifter having a plurality of screens, 10 their meshes differing in degrees of fineness, so that flour or similar material passing therethrough at one operation effects a saving of time. Another object is to provide a flour sifter of such construction that 15 foreign substances or the coarse parts of flour not passing meshes may be conveniently removed from the screens.

With the foregoing objects in view and others to be mentioned hereinafter, the invention consists of the novel construction, combination and arrangement of parts as described herein and claimed, and as illustrated in the accompanying drawing, wherein,

25 Fig. 1 is a plan view of a flour sifter embodying my invention. Fig. 2 is a view of the same in side elevation, the sleeve or cylindrical body of the sifter being in longitudinal section. Fig. 3 is a side view of 30 one of the sections of the sleeve, the scale being reduced. Fig. 4 is a side view of a section of the sleeve, said section operating as a slide for engaging the section shown in Fig. 3. Figs. 5, 6 and 7 are plan views 35 of the screens employed, said screens having meshes varying in fineness.

Referring now to the drawing for a more particular description, I provide a cylindrical container or upright sleeve consisting 40 of a segmental plate or section 8 and a second segmental plate section or slide 9, said first named section being provided in its inner side with grooves 10, these grooves being formed at right-angles to its longitudinal axis, near its lower end.

45 Numerals 11 indicate parallel slots formed in the part 8, each being adjacent to and immediately above, midway between the ends of a groove 10; and at 12 are indicated terminal flanges or guides which are provided for said section 8.

50 Numerals 13, 14 and 15 respectively indicate screens, each provided with a housing-rim, these screens having meshes of varying degrees of fineness, as compared with each

other, and adapted to engage in the grooves 10, the rims of said screens 13, 14 and 15 being respectively indicated at a, b and c.

At 16 are indicated agitator-blades adapted to lie upon the screens, each having 60 an arm 17 extending outwardly of a slot 11.

The segmental section 9 of the sleeve is adapted to engage the parallel guides 12, and when so in engagement, members 8 and 9 form the complete sleeve, and the section 65 9 is adapted to have slidable movements in said guides, and is provided with a handle 18.

Any suitable means may be provided for 70 swinging the agitator blades simultaneously, the means herein shown consisting of a yoke 19 provided with a pivot-pin 20 which traverses the outer end-portions of the arms 17 of the agitator-blades, the arms of the yoke being pivotally mounted upon 75 brackets *a* which are secured to the sleeve-section 8.

In operation, the section 9 being mounted upon the section 8, flour to be sifted, obviously, may fill that part of the sifter 80 above the uppermost screen. By swinging the yoke horizontally the blades 16 will be simultaneously reciprocated, the particles of flour having a degree of coarseness too great to pass through the meshes, being 85 detained.

It is understood that the weight of the sifter and its contents must be supported, manually, by use of the handle 18, and to prevent an upward slidable movement of 90 the section 9 relative to the part 8, during operation, pivotally mounted lug *d* are provided for the section 9, adapted to be swung horizontally for engaging the lower edge of the section 8, which prevents such 95 movement.

When the operation of sifting has been completed, the section 9 may have a sliding movement to permit removal of the coarse parts of flour or foreign substances which 100 did not pass through the screens, and by manually swinging the lugs *d* from their engagement with the section 8, the section 9 may have an upward sliding movement 105 for this purpose.

The advantages to be derived by use of the herein described sifter will be appreciated since, by a single operation, the flour will be sifted as many times as the number 110 of screens employed, the flour being sifted

first by a comparatively coarse screen and thereafter by screens of greater fineness, which thoroughly mixes the flour and operates to economize the time of an operator, each upper screen preventing coarse parts of flour from obstructing the screen of greater fineness next below it.

I claim as my invention,—

1. In a flour sifter, the combination with a container having an upright, transversely curved side wall provided with flanges at its longitudinal edges, said container being provided with screens and means for agitating flour on the screens, of an upright, segmental plate provided with a handle and adapted to be disposed with its longitudinal edges inwardly of said flanges and normally adapted to have sliding movements longitudinally of the container, and a plurality of lugs on the segmental plate adapted to be moved into engagement with the container for limiting a sliding movement in

one direction of said plate, relative to said container.

2. In a flour sifter, the combination with an upright container having a transversely curved side wall with upright edges terminating adjacent to each other, said container being provided with screens and agitating devices, of an upright, segmental plate normally disposed between the upright edges and slidably mounted on the side wall of the container, a handle on the segmental plate, and devices on said plate for engaging the container for limiting a sliding movement, in one direction, of said plate, relative to said container.

In testimony whereof, I have affixed my signature in presence of two witnesses.

JULES H. STEAN.
